DESIGN FOR A TOY CONFECTION

John W. Glenn, Buffalo, N. Y.

Application January 31, 1938, Serial No. 74,753

Term of patent 3½ years

To all whom it may concern:

Be it known that I, John W. Glenn, a citizen of the United States, residing at Buffalo, in the county of Erie and State of New York, have invented a new, original, and ornamental Design for a Toy Confection, of which the following is a specification, reference being had to the accompanying drawing, forming part thereof.

In this drawing:

Fig. 1 is a side elevation of the toy confection showing my new design.

Fig. 2 is a top plan view thereof.

Fig. 3 is a bottom plan view of the same.

Fig. 4 is a front elevational view of the same.

Fig. 5 is a rear elevational view of the same.

I claim:

The ornamental design for a toy confection as shown.

JOHN W. GLENN.
